IRONING MACHINE

Frederick K. Mueller, Berwyn, Ill.

Application January 24, 1938, Serial No. 186,521

10 Claims. (Cl. 38—47)

This invention relates to ironing machines, and has to do with ironing machines intended more particularly for domestic use.

In ironing articles by hand, it is customary to move the iron over the articles in first one direction and then another, such directions being in general substantially perpendicular to one another. This has the effect of smoothing out the articles and preventing wrinkles or creases therein. Further, the changes in direction of movement of the iron, in contact with the article, subjects the threads of the fabric to substantially the same pressure and tension both lengthwise and transversely of the article, avoiding any distortion thereof and imparting thereto a desirable smoothness and sheen. Hand ironing thus produces a noticeably better finish to the articles than it is possible to accomplish by machine ironing, as usually practiced, but is open to the objection that it involves more time and labor than ironing by machine.

My invention is directed primarily to the provision of an ironing machine which, in operation, closely approximates hand ironing and imitates parts to the articles that smoothness and sheen characteristic of articles ironed by hand. Broadly, it is an object to provide an ironing machine having two cooperating ironing members, one of which is a rotating roll, movable into and out of cooperating relation and capable of relative reciprocation lengthwise of the roll, the roll being driven by a motor and means being provided to effect the desired relative movements of the members. A further and more specific object is to provide simple and efficient means for moving a cooperating shoe lengthwise of the roll, in cooperating relation therewith. It is also an object to provide means for optionally stopping relative reciprocation of the ironing members in predetermined relation one to the other. Further objects and advantages will appear from the detail description.

In the drawings:

Figure 1 is a rear view, partly broken away, of an ironing machine embodying my invention, showing the shoe at the limit of its movement in one direction lengthwise of the roll;

Figure 2 is a view similar to Figure 1, but showing the shoe at the limit of its movement in the other direction lengthwise of the roll;

Figure 3 is a fragmentary sectional view, on an enlarged scale, taken substantially on line 3—3 of Figure 2, parts being shown in elevation and broken away;

Figure 4 is a sectional view, on an enlarged scale, taken substantially on line 4—4 of Figure 1, certain parts being shown in elevation and certain other parts being shown partly broken away and in section;

Figure 5 is a fragmentary vertical sectional

view, on an enlarged scale, taken in the plane of the roll drive shaft axis and at right angles to Figure 4, certain parts being shown in elevation, with certain other parts broken away and other parts shown partly broken away and in section; 5

Figure 6 is a sectional view taken substantially on line 6—6 of Figure 4, certain parts being shown in plan and other parts being shown partly broken away and in section; certain other parts being omitted for clearness of illustration; 10

Figure 7 is a fragmentary sectional view taken substantially on line 7—7 of Figure 8, certain parts being shown in elevation; and

Figure 8 is a view similar to Figure 6, showing a modified form of means for reciprocating the 15 shoe operating shaft.

I have illustrated my invention, by way of example, as embodied in an ironing machine which is, in general, similar to that disclosed in Patent No. 2,054,631, issued September 15, 1936, to Rudolph W. Janda, for Ironing machine. The machine comprises a suitable stand having a top bed plate 9 supported by depending legs 10. A main gear housing 11, closed at its outer end by a removable cover plate 12, is appropriately mounted upon bed plate 9, at one end thereof, and extends downward therethrough. A sleeve 13 is formed integrally with, and extends upward from, bottom wall 14 of housing 11. 20

A worm gear housing 15, appropriately secured to and depending from housing 11, is provided with a collar 16 aligned with a depending bearing boss 17, the latter receiving the lower end portion of a shaft section 18, which passes upward through collar 16. A worm wheel 19 is secured upon shaft section 18 and meshes with a worm 20 fixed on a shaft 21 rotatably mounted in housing 15, the latter shaft being driven, through a flexible coupling 22, by an electric motor 23 suspended from bed plate 9 by hanger 24 brackets 24. 30

Shaft section 18 passes upward through a bushing 25, mounted in sleeve 13 with its lower end contacting the upper end of hub 19a of worm wheel 19. Bushing 25 extends above sleeve 13, 45 through an eccentric and clutch assembly designated generally by the reference number 26. The assembly 26 is similar to the eccentric and clutch assembly disclosed in the above identified patent to Rudolph W. Janda, and in Patent No. 1,867,839, issued July 19, 1932, to Rudolph W. Janda, and need not be illustrated nor described here in detail, a brief description thereof being sufficient.

Assembly 26 comprises a member 27, loose on bushing 25, having a depending eccentric 27a seating at its lower end upon the upper end of sleeve 13. Suitable means is provided for clutching and declutching member 27 to and from shaft section 18. This clutch means is controlled by a 50 55 60

trip finger 28 pivoted to the front wall 29 of gear housing 11 and normally held in operative position. Finger 28 is connected, by a rod 30, to an arm 31 secured upon a pin 32 loosely mounted through a lug 33 extending inward from upper portion 29a of front wall 29 of housing 11. An angle lever 34 has its lower end secured upon pin 32, extends through a slot 35 in wall portion 29a, and is provided at its outer end with a head 10 or knob 36. Lever 34 normally is held in its outer position by a coil wire spring 37 disposed about pin 32, with one arm engaged beneath arm 31 and its other arm extending across the top of lug 33, in rear of lever 34 and effective as a stop 15 for limiting outward movement thereof. Spring 37 also serves normally to hold trip finger 28 in normal position, effective for declutching member 27 from shaft section 18 and maintaining it de-clutched.

20 When lever 34 is moved inward a short distance, trip finger 28 is moved into inoperative position, releasing the clutch means, which is spring actuated, thus clutching member 27 to shaft section 18 for rotation therewith. Lever 25 34 is moved inward but momentarily, and is then released, returning trip finger 28 to operative position. Rotation of member 27 with shaft section 18 continues during a predetermined portion, about 180°, of the ensuing rotation of shaft 30 section 18, at which time an element of the clutch contacts finger 28 and member 27 is declutched from shaft section 18. In this manner member 27 is clutched to shaft section 18, turns therewith to a predetermined extent, and is then automatically declutched therefrom. The particular clutch means employed is not of the essence of my invention, though I preferably employ the clutch means disclosed in Patent No. 1,867,839, above referred to. Suffice it to state that suitable means is provided for optionally clutching member 27 to shaft section 18 for rotation therewith to a predetermined extent, and declutching member 27 from the shaft section when it has been turned to the desired extent.

40 Shaft section 18 is disposed below and coaxially with an upper shaft section 38 rotatably mounted through a relatively thick rib 39 extending from the inner end wall of gear housing 11. Shaft section 38 is provided, at its lower 45 end, with a reduced squared stud 38a which fits into a corresponding bore in the upper end of a coupling member 39. Shaft section 18 is provided, at its upper end, with a reduced squared stud 18a which fits into a corresponding bore in 50 the lower end of member 39. In this manner, the two shaft sections are coupled together for rotation as a unit.

An ironing roll 40, provided with a suitable pad, extends from gear housing 11 inward over 55 bed plate 9 thereabove and parallel therewith. Roll 40 is mounted for rotation about its axis, and is secured to a shaft 41, extending into gear housing 11 and appropriately mounted for rotation. Conveniently the roll 40 and shaft 41 60 are mounted and secured together in the manner disclosed in the two above identified Patents No. 1,867,839 and No. 2,054,631. The particular manner of mounting roll 40 and shaft 41, and connecting them together, is not of the essence of 65 my invention, and need not be set forth in greater detail. Suffice it to state that the roll and the shaft are rotatably mounted and connected together in an appropriate manner.

70 Roll shaft 41 is driven, as desired, from shaft section 38 through a change speed gearing as-

sembly indicated generally by the reference number 42. The assembly 42 is similar to that disclosed in Patent No. 2,054,631, and need not be described here in detail. It has associated therewith suitable control means whereby shaft 41, and consequently roll 40, may be driven at either one of two speeds, or rotation of the roll may be prevented, as desired. The control means is operated by a control rod 43 mounted for turning movement through a boss 44 at the bottom of 10 upper portion 29a of front wall 29 of gear housing 11. Rod 43 also extends through and projects outward beyond a plate 44a seating upon the outer face of boss 44, suitably secured thereto and extending downward therefrom to the upper surface of bed plate 9. An operating handle 46 is secured upon the outer end of rod 43, the inner end of which is connected, by a universal connection 47, to the forward end of a turnably mounted control member 48. Means is also provided, comprising a two-part control lever 49 and a cooperating eccentric 50 rotatable with member 27, for automatically enabling and disabling the drive between assembly 42 and roll shaft 41, in accordance with predetermined turning of the latter. The variable speed driving means and associated control means, referred to, are fully disclosed in Patent No. 2,054,631 and need not be described in greater detail here. If desired, any other suitable means may be provided for driving the roll shaft, such, for example, as the means disclosed in Patent No. 1,867,839 or in Patent No. 2,026,345, issued December 31, 1935, to Rudolph W. Janda, for Ironing machine. It will be seen, from what has been said, that the 30 shaft sections 18 and 38, together with coupling member 39, constitute a unit or shaft and that this shaft has appropriate driving connection to the roll for driving or rotating the latter from the motor 23. The ironing machine illustrated 35 and so far described, is, in general, similar to that disclosed in Patent No. 2,054,631.

Gear housing 11 is provided, at its rear inner corner, with an interior boss 51 (Fig. 6), bored from its outer face to provide a cylindrical recess 52, and an exterior tubular cylindrical boss 53, the bore of which is coaxial with and of less diameter than recess 52, providing a shoulder 54 at the inner end thereof. An elongated tube or sleeve 55 is mounted at its outer end in boss 50 53, extends therefrom along bed plate 9 in close proximity thereto and parallel with roll 40, and has its inner end portion secured in a bracket 56 (Figs. 1 and 2) in an appropriate manner, as by a set screw 57 (Fig. 3), which bracket is bolted or otherwise suitably secured to bed plate 9. A shoe operating shaft 58 extends through bushings 59 mounted in the ends of sleeve 55 (Figs. 3 and 6), and is mounted therein for axial reciprocation and rocking movement about its axis. 60 Shaft 58 extends through the outer end of sleeve 55 and boss 51 into gear housing 11, as shown in Figure 6, and also projects through the inner end of sleeve 55 a considerable distance beyond bracket 56, as shown in Figures 1 and 2.

A shoe operating arm 60 is suitably secured, as by means of a pin 60a, on the inner end of shaft 58, and is straddled by a bifurcated shoe supporting arm 61, loosely mounted at its lower end on shaft 58 and confined against relative 7 movement lengthwise thereof by arm 60. Means, including an emergency release lever 62, is provided for normally coupling the arms 60 and 61 together for movement as a unit. An ironing shoe 63, conveniently heated by electrical re- 7

sistance elements contained therein, is mounted upon the upper end of arm 61 for movement therewith. This shoe is of known construction and has a concaved ironing or operating surface conforming in transverse curvature and in length to the cooperating surface of the roll 40. It will be clear that the shoe 63 is mounted on shaft 58 and connected thereto for movement therewith, when the arms 60 and 61 are coupled together. The arrangement of the arms 60 and 61 and the associated coupling means and the shoe is similar to that disclosed in Patent No. 2,026,345. It is not essential to my invention, however, that this particular arrangement be used, and any other suitable means may be provided for supporting the shoe and operatively connecting it to its associated operating shaft.

An arm 64 (Figure 4) is secured by a pin 64a (Figure 6) upon the outer end of shoe operating shaft 58, within gear housing 11, and extends downward therefrom. The lower end of arm 64 is connected, by a universal connection 65, to the rearward end of a connecting rod 66 provided at its forward end with an eccentric strap 67 fitting about eccentric 27. Turning of eccentric 27 to predetermined extent, into one position, turns shaft 58 about its axis in one direction, and turning of the eccentric from that position through 180° into its other position, turns shaft 58 about its axis in the other direction. In this manner eccentric 27 serves to turn shoe operating shaft 58 about its axis in alternately opposite directions and to predetermined extent, effective for moving the shoe 63 to the roll 40 in cooperating relation therewith and moving the shoe away from the roll out of such cooperating relation.

Shoe operating shaft 58 may also be reciprocated axially, for reciprocating the shoe lengthwise of the roll. A lever 68 is pivoted at its mid-portion for movement about a vertical axis, on a stud 69 screwed into a boss 70 integral with wall 71 of gear housing 11, as shown in Figure 4. At its rearward end lever 68 bears upon a bearing ball 72 (Figure 6) seated in a corresponding recess in the outer end of shaft 58. A coil compression spring 73, mounted about shaft 58, is confined under compression between shoulder 54 and the upper end of arm 64, and yieldingly urges shaft 58 outward. Coupling member 39 is provided at its mid-portion with an eccentric 74 fixed thereto, conveniently formed integrally therewith. Lever 68 carries, a short distance from its forward end, a roller 75 mounted for rotation about a vertical axis and bearing upon the operating surface of eccentric 74, which rotates in a clockwise direction, as indicated by the arrow in Figure 6, in the rotation of the roll drive shaft, comprising sections 18 and 38 and 60 the coupling member 39. The cam 74 and lever 68 cooperate to limit outward movement of shaft 58 and to move the latter inward in opposition to spring 73, as will be clear from Figure 6. In this manner shaft 58 is reciprocated axially, as indicated by the double-headed arrow *a*, reciprocating shoe 63 lengthwise of roll 40. The provision of the universal connection 65, in conjunction with the ability of eccentric strap 67 to turn slightly about eccentric 27, if necessary, eliminates possibility of binding of parts incident to reciprocation of shaft 58.

In Figure 1 shoe 63 is shown in the position which it occupies when shoe operating shaft 58 has been moved by spring 73, under control of lever 68 and eccentric 74, into its outermost po-

sition, with corresponding movement of the shoe, indicated by arrow *a*¹. At that time, the shoe projects a short distance beyond the left hand end of roll 40, as viewed in Figure 1, and shoe supporting arm 61 is disposed adjacent but spaced a slight distance from the inner end of bracket 56, as shown, arms 60 and 61 being appropriately disposed upon shaft 58 to that end. In Figure 2 shoe 63 is shown in its other extreme position, into which it is moved in the direction indicated by the arrow *a*², incident to corresponding movement of shaft 58. It will be noted that the ends of shoe 63, in the latter position thereof, are flush with the ends of the roll, so that the operating surface of the shoe is coextensive lengthwise with the operating surface of the roll, for a purpose presently to be described.

In some cases, as when ironing pleated garments or certain fabrics, it may be desirable not to reciprocate the shoe. Accordingly, I have provided suitable means to that end. Lever 68 is provided, at its forward end, with an upwardly projecting head 68a the outer face of which is convexed in plan, as shown in Figure 4. Head 68a is provided, adjacent the inner side thereof, with a bore 68b adapted for reception of a reduced stud 76, at the rearward end of a locking rod 77 slidable through plate 44a and a boss 78, the latter projecting forward from wall 29 of gear housing 11, below and adjacent boss 44. Rod 77 is provided, at its outer end, with an operating knob 79 and, in the portion thereof operating through boss 78, with two circumferential grooves 80 and 81. A locking ball 82, yieldingly urged upward by a coil compression spring 83, disposed within bore 84 in boss 78 and confined between the ball and a screw plug 85 closing the lower end of the bore, is disposed to engage into groove 80 in the inner position of rod 77, and groove 81 in the outer position of this rod.

Bore 68b is so disposed as to be aligned with stud 76 when head 68a of lever 68 is in its outermost position, at which time the point on the circumference of eccentric 74 most remote from the axis of the roll drive shaft is in contact with roller 75 and shoe operating shaft 58 is in its innermost position, shoe 63 then being in the position shown in Figure 2. In order to stop reciprocation of the shoe, rod 77 is pushed rearward until stud 76 contacts head 68a, and is then maintained under rearward pressure until bore 68b is brought into alignment with stud 76, the latter then entering bore 68b and locking the forward end of lever 68 against movement. When stud 76 has fully entered bore 68b, ball 82 engages into groove 80, locking rod 77 against accidental outward or forward movement. In the continued rotation of eccentric 74 the latter may touch roller 75 but exerts no effect upon lever 68, due to the position in which the latter is held. If desired, bore 68b may be slightly inclined relative to stud 76, in proper direction and extent such that by forcing stud 76 into bore 68b the forward end of lever 68 is moved outward a slight distance beyond the outermost position to which it is moved by eccentric 74. This additional movement may be slight, just sufficient to assure that the eccentric 74 will clear roller 75, and will not noticeably or objectionably affect the position of shoe 63 relative to roll 40, as shown in Figure 2. Head 68a is of sufficient extent to preclude possibility of disposing stud 76 in such position as to lock the forward end of lever 68 in its inner position, in opposition to the outward movement imparted thereto by eccentric 74. Any other suit-

able means may be provided for stopping reciprocation of the shoe, within the broader aspects of my invention.

Preferably, when reciprocation of the shoe is stopped the latter is disposed with the ends thereof flush with the ends of the roll, as previously stated and shown in Figure 2. Stopping the shoe in that position relative to the roll assures that the operating surface of the shoe extends the full length of the operating surface of the roll. That has the advantage of preventing marking or creasing of an article being ironed, such as might occur if an end of the shoe were disposed inward of the roll from the corresponding end thereof.

Subject to the above noted exceptions, the shoe is reciprocated lengthwise of the roll during the ironing operation. The reciprocating shoe acts upon the articles in two directions substantially perpendicular one to the other, lengthwise of the roll and transversely thereof. This operation closely approximates hand ironing, with the result that the articles have imparted thereto a smoothness of finish and sheen substantially equal to that obtainable by experienced hand ironing.

In the modification illustrated in Figures 7 and 8, shoe operating shaft 58, when reciprocated, is positively moved in both directions. Bore 52a of boss 51a is equal in diameter to and forms a continuation of the bore of boss 53. The outer end portion of shaft 58a is reduced, providing a neck 86 with shoulders 87 and 88 at the ends thereof. A lever 89, pivoted on stud 69, is provided at its rearward end with a vertically disposed form 90, which straddles neck 86 with the arms of this form contacting shoulders 87 and 88, the latter being of slightly rounded or frusto-spherical shape as shown. Lever 89 is provided, at its forward end, with a horizontally disposed form 91, which straddles an eccentric 92 loose upon a coupling member 39a, similar to coupling member 39 except that it is provided with an outwardly extending circumferential flange 93 upon the upper face of which eccentric 92 seats. Flange 92 is provided with a series of arcuate notches 94 disposed to receive a locking pin 95 vertically slidable through cam 92. Pin 95 is yieldingly urged downward by a leaf spring 96, secured at one end in a stepped groove 97 extending from the upper face of cam 92, the free end of this spring bearing upon a finger 98 fixed in pin 95, this finger operating in groove 97 and preventing turning of finger 95 while also limiting downward movement thereof.

Pin 95 is provided, at its upper end, with an integral trip arm 99 disposed at right angles thereto and projecting outward therefrom substantially radial to eccentric 92. Arm 99 cooperates with a tripping cam 100 secured upon the rearward end of a rod 101 non-rotatably and slidably mounted through boss 18 and plate 44a. Cam 100 is curved inward toward coupling member 39a, as in Figure 8, with its rearward end rounded and its upper face inclined upward and forward to a transverse horizontal surface 100a, as indicated in Figure 7, and is movable, by means of rod 101, from its inoperative position, shown in full lines in Fig. 8, into its operative position, indicated in the latter figure, and in Figure 7, by dot and dash lines. Rearward movement of rod 101 may be limited in any suitable known manner. In its operative position, cam 100 is disposed above and adjacent eccentric 92, with its inclined upper surface in the path of travel 75 of trip arm 99, when the eccentric is rotated

clockwise as indicated by the arrow in Figure 8. As arm 99 moves relative to cam 100, it contacts the inclined cam surface and, in the continued turning of eccentric 92, is forced upward in opposition to spring 96 until it enters upon flat 5 surface 100a. This raises the lower end of pin 95 above the upper face of flange 93, declutching the eccentric 92 from coupling member 39a, the latter continuing to rotate without affecting the eccentric. Pin 95 is so disposed that the eccentric 92 is declutched when the forward end of lever 89 is in its outermost position, shoe 63 being then in the position shown in Figure 2, in which position it is held by eccentric 92, the latter being then in dead center position with respect to coupling member 39a and fork 91.

When it is desired again to reciprocate the shoe 63, cam member 100 is moved into inoperative position, releasing pin 95 which is moved downward by spring 96. In its downward movement 20 pin 95 either enters directly one of the notches 94 in flange 93, or contacts the upper face of this flange. In the latter event, the continued rotation of coupling member 39a brings a notch 94 beneath pin 95 which immediately enters thereinto. After pin 95 enters a notch 94, slight turning of coupling member 39a brings the following end wall of the notch into contact with the pin, causing eccentric 92 to rotate with member 39a. Any suitable means, other than that shown, may 30 be provided for controlling reciprocation of the shoe, the particular means illustrated being exemplary only.

With the exceptions above described, the construction and operation of the modified form of 35 machine illustrated in Figures 7 and 8 are the same as in the form illustrated in Figures 1 to 6, inclusive, and need not be described in greater detail. In both forms, the roll is driven by the motor 23, which conveniently also operates the 40 means for moving the shoe to and from the roll and the means for reciprocating the shoe, and the latter is automatically positioned, when reciprocation thereof is stopped, with its ends flush with the ends of the roll. In the broader aspects of 45 my invention, it is not essential that the shoe be operated by power derived from the motor 23. Any other suitable means may be provided for imparting the desired movements to the shoe, or the desired relative movements to the cooperat- 50 ing ironing members.

As above indicated, and as will be understood by those skilled in the art, changes in construction and arrangement of parts of my invention may be resorted to without departing from the 55 field and scope thereof, and I intend to include all such variations, as fall within the scope of the appended claims, in this application in which the preferred forms only of my invention have been shown.

I claim:

1. In an ironing machine, a rotatably mounted roll, a reciprocably and rockably mounted shoe operating shaft, a shoe cooperating with said roll connected to said shaft for movement therewith and movable to and from said roll by rocking of said shaft, a motor having driving connection to said roll, means effective for turning said shaft to predetermined extent in alternately opposite directions, and means for reciprocating said shaft, 70 when said shoe is in cooperating relation to said roll.

2. In an ironing machine, a rotatably mounted roll, a reciprocably and rockably mounted shoe operating shaft, a shoe cooperating with said roll 75

- connected to said shaft for movement therewith and movable to and from said roll by rocking of said shaft, a motor having driving connection to said roll, means effective for turning said shaft to predetermined extent in alternately opposite directions, means for reciprocating said shaft, when said shoe is in cooperating relation to said roll, and means effective for optionally disabling said reciprocating means.
10. 3. In an ironing machine, a rotatably mounted roll, a shoe operating shaft disposed below and in rear of said roll parallel therewith, said shaft being mounted for axial reciprocation and for rocking movement about its axis, a shoe cooperating with said roll disposed in rear thereof mounted on and movable with said shaft, said shoe being moved to and from said roll by rocking of said shaft, a motor having driving connection to said roll, motor operated means effective for turning said shaft to predetermined extent in alternately opposite directions, and motor operated means effective for reciprocating said shaft, when said shoe is in cooperating relation to said roll.
15. 4. In an ironing machine, a rotatably mounted roll, a motor, a roll drive shaft driven by said motor and driving said roll, a shoe operating shaft parallel to said roll mounted for axial reciprocation and rockable about its axis, a shoe cooperating with said roll mounted on and movable with said shoe shaft, said shoe being moved to and from said roll by rocking of said shoe shaft, means actuated by said drive shaft effective for turning said shoe shaft to predetermined extent in alternately opposite directions, and means effective for reciprocating said shoe shaft comprising connections between the latter shaft and said drive shaft.
20. 5. In an ironing machine, a rotatably mounted roll, a motor, a roll drive shaft driven by said motor and driving said roll, a shoe operating shaft parallel to said roll mounted for axial reciprocation and rockable about its axis, a shoe cooperating with said roll mounted on and movable with said shoe shaft, said shoe being moved to and from said roll by rocking of said shoe shaft, means actuated by said drive shaft effective for turning said shoe shaft to predetermined extent in alternately opposite directions, and means effective for reciprocating said shoe shaft to and from said roll by rocking of said shoe shaft, said shoe being moved to and from said roll by rocking of said shoe shaft, means actuated by said drive shaft effective for turning said shoe shaft to predetermined extent in alternately opposite directions, an eccentric disposed about said drive shaft, a lever provided at one end with a fork straddling said eccentric and having connection at its other end to said shoe shaft effective for reciprocating the latter responsive to rotation of said eccentric, and means for clutching and declutching said eccentric to and from said drive shaft.
25. 6. In an ironing machine, a rotatably mounted roll, a reciprocably and rockably mounted shoe operating shaft, a shoe cooperating with said roll connected to said shaft for movement therewith and movable to and from said roll by rocking of said shaft, means for driving said roll, means for turning said shaft to predetermined extent in alternately opposite directions, means for reciprocating said shaft, said shoe having an operating surface equal in length to that of said roll, and means for stopping reciprocation of said shaft with the ends of said shoe flush with the ends of said roll.
30. 7. In an ironing machine, the combination of a rotatably mounted roll, an ironing shoe cooperable therewith, adjacent the rear side of said roll, a shoe supporting member extending downwardly from said shoe, said member being rotatably connected adjacent the lower end thereof to the machine for positively supporting said shoe in operative position relative said roll, the axis of said member being parallel and co-axial to the axis of said roll, rotation of said member about said axis operative to carry said shoe towards and rearwardly away from said roll, and means for reciprocating said member and shoe in a direction parallel to its axis while said shoe is supported in cooperable operative relation with said roll during rotation of the latter.
